(57) **CLAIM**

The ornamental design for a fluid handling module, as shown and described.

DESCRIPTION

FIG. 1 is a first isometric view of a fluid handling module; FIG. 2 is a second isometric view of the fluid handling module;

FIG. 3 is a front elevational view of the fluid handling module;

FIG. 4 is a left side view of the fluid handling module; FIG. 5 is a rear elevational view of the fluid handling module;

FIG. 6 is a right side view of the fluid handling module; FIG. 7 is a top plan view of the fluid handling module; and, FIG. 8 is a bottom plan view of the fluid handling module. The broken lines in the Figures represent portions of the fluid handling module and form no part of the claimed design.

1 Claim, 8 Drawing Sheets
